(57) **CLAIM**

The ornamental design for a multiple light configuration for a vehicle, as shown and described.

DESCRIPTION

FIG. 1 is a perspective view of a multiple light configuration for a vehicle showing the left side of the vehicle showing my new design;

FIG. 2 is a front elevation view thereof; and,

FIG. 3 is a front elevation view of a multiple light configuration for a vehicle showing the right side of the vehicle.

The broken line portions of the drawing is meant to illustrate environmental structure for which the present invention is intended and forms no part of the claimed design.
